UNITED STATES PATENT OFFICE.

SOREN HANSSON, OF BUTLER, PENNSYLVANIA, ASSIGNOR TO JOHN H. ALLMAN,
TRUSTEE, OF BUTLER, PENNSYLVANIA.

DRAFT-GEAR APPARATUS.

Application filed October 9, 1925. Serial No. 61,452.

My invention relates to draft gear apparatus, and particularly to a means for connecting a draw bar yoke with a coupler shank.

5 One object of my invention is to provide an arrangement whereby the coupler may have pivotal movement with respect to the draw bar yoke, as when a train is passing around a curve, or to permit the coupler parts to accommodate themselves to abnormal positions, such as misalignment through unevenness of road-bed, etc.

10 Another object of my invention is to simplify and improve generally the structure and operation of draft gear apparatus.

15 Some of the forms which my invention may take are shown in the accompanying drawing, wherein Fig. 1 is a view, partially in plan and partially in section, of a portion of a draft gear structure embodying my invention; Fig. 2 is a view showing a portion of the apparatus of Fig. 1, removed from the draft sills; Fig. 3 is a sectional view on the line 3—3 of Fig. 4; Fig. 4 is 20 a longitudinal sectional view of the apparatus of Fig. 2; Fig. 5 is a view similar to Fig. 3 but showing a modified form of connection between the yoke head and the draw bar yoke, and Fig. 6 is a view showing still 25 another modification.

30 This invention constitutes an improvement upon that disclosed in my Patent No. 1,556,219, issued October 6, 1925.

35 The apparatus is shown as applied to draft sill members 7 that may be of any desired form, and are provided with rear stop lugs 8 and front stop lugs 9 against which follow blocks 10 and 11, respectively, seat.

40 The follower blocks 10 and 11 extend through a forged yoke 12 that may support the usual springs and other shock absorbing elements (not shown).

45 The leg portions of the yoke 12 are preferably enlarged at their forward ends, for greater strength, and are provided with circular openings, by means of which engagement is made with a yoke head which is composed of members 14 and 15. The member 14 is provided with a pair of lugs 16 of 50 generally semi-circular form, as shown more clearly in Fig. 2, and the head member 15 is provided with a pair of semicircular lugs 17. The lugs 16 and 17 extend through the cir-

55 cular openings in the yoke 12 and are provided at their mid portions with complementary offset portions as indicated at 18, so that the head members 14 and 15 will have interlocking engagement with one another and be held against relative movement, thus strengthening and supporting one another. 60 The head members 14 and 15 are also provided with openings 19 through which a draw bar key 20 may extend, as shown in Fig. 1, to effect a connection between a draw bar or coupler shank 22 and the yoke head, 65 in somewhat the usual manner.

70 The outer ends of the lugs 16 and 17 are upset or peened over as shown more clearly in Figs. 3 and 4 and, by reason of the combined circular contour of each pair of lugs 16—17, the head 14—15 may rotate about the vertical axis thus afforded, as indicated in Fig. 1, without moving the yoke 12. This arrangement is particularly useful 75 when a train of cars is passing around a curve, since the couplers are then moved from their normal positions in alignment with the longitudinal center lines of the cars. Were the coupler rigidly connected to the draw bar yoke, binding would sometimes take place, resulting in damage to 80 parts of the draft gear structure or interfering with the proper functioning of the cushioning elements of the draft gear.

85 It will be understood that the ends of the projections 16 and 17 are not upset so tightly against the sides of the yoke 12 as to interfere with the swiveling movement of the members 14 and 15.

90 In Fig. 5 I have shown a structure wherein yoke head members 14^a and 15^a, which correspond to the members 14 and 15 of Fig. 3, are modified by having shoulder portions 21 formed thereon. Collars 22^a are placed upon the shoulder portions 21 and the outer ends 95 16^a and 17^a of the members 14^a and 15^a upset against the collars. The peripheral portions of the collars 22^a seat within circular recesses within the legs of the yoke 12, so that the coupler head may have swiveling 100 movement in the yoke.

105 In Fig. 6 still another form of swivel mounting is shown, wherein a collar 23 surrounds the extensions of the head members 14^b and 15^b and is held in place thereon by upsetting of the extensions 16^b and 17^b. The

collar 23, as in the case of collar 22^a of Fig. 5, has bearing engagement with the sides of the yoke 12.

I claim as my invention:

- 5 1. Draft gear structure comprising a yoke, a pair of head members disposed between the forward end portions of said yoke, a pivotal connection between said head members and said yoke, and means for connecting a draw bar to said head members.
- 10 2. Draft gear structure comprising a yoke having circular openings in its ends, a pair of head members having semicircular portions extending through said openings, and means for connecting a draw bar to said head members.
- 15 3. Draft gear apparatus comprising a yoke, two head members disposed between

the legs of said yoke and having interlocking engagement with one another, means 20 for pivotally connecting said members to said yoke, and means for connecting a draw bar yoke to said members.

4. A yoke for draft rigging and the like, comprising a body portion having spaced 25 side members each provided with a recess, a head portion composed of two sections disposed between said side members, and lugs on both ends of each section, both lugs on adjacent ends of the sections extending into 30 the recess which is adjacent thereto and having pivotal movement therein.

In testimony whereof I, the said SOREN HANSSON, have hereunto set my hand.

SOREN HANSSON.
